(57) **CLAIM**

The ornamental design for a tubing connector for breast pumps, as shown.

DESCRIPTION

FIG. 1 is a perspective view of a tubing connector for breast pumps showing my new design;

FIG. 2 is another perspective view thereof;

FIG. 3 is an elevational front view thereof, the elevational rear view being the mirror image of FIG. 3;

FIG. 4 is an end view from the left thereof;

FIG. 5 is an end view from the right thereof; and,

FIG. 6 is an elevational bottom view thereof, the elevational top view being the mirror image of FIG. 6.
